KNITTED HOSIERY

Jack Kugelman, Philadelphia, Pa.

Application March 24, 1934, Serial No. 717,273

2 Claims. (Cl. 66—178)

This invention relates generally to full-fashioned knitted hosiery and more particularly to improvements in the nature of the knitted fabric of which the sheer, non-reinforced portion of the stocking is comprised, as well as in the method of producing the said fabric.

Heretofore and prior to this invention it has been the general practice in the art to knit the sheer, non-reinforced portions of the stocking, such as the leg and upper portion of the foot thereof, of a single yarn, the knitting of the fabric being effected in such manner that the successive interlooped knitted courses thereof are each composed of the same yarn, which latter may be formed, for example, of silk having a certain number of threads twisted together a certain number of turns per inch. It is also a known practice in the art to knit the said sheer, non-reinforced portions of the stocking of a plurality of separate and distinct yarns, the knitting of the fabric in such case being effected by the use of a plurality of carriers corresponding in number to the number of separate yarns employed, the carriers being operated selectively and in such predetermined order that no two or more successive courses of the fabric are composed of the same yarn. In this latter method, the several yarns are delivered to the knitting head of the machine from separately mounted cones or sources of supply, it being a characteristic of the method that the several yarns so employed are as identical with respect to each other as it is possible to obtain, insofar as the number of threads, turns per inch, denier, color and other such characteristics of each yarn are concerned.

Irrespective of whether a single length of yarn is employed to knit all of the interlooped courses of the hosiery fabric or a plurality of independent lengths of yarns are employed selectively and in predetermined sequence to knit the several courses, it is nevertheless a common characteristic of the fabric so knitted that the wales thereof are quite pronounced and clearly discernible to the eye, the wales, of course, being the longitudinally extending lines of loops formed by the needles of the knitting machine. It is the presence of these wales which impart to the knitted hosiery fabric the conventional appearance so well known to the art and to the wearers of the hosiery. Moreover, in the fabrics produced in the conventional manners above described, that is, by the use of a yarn or yarns of substantially identical character in all of the interlooped courses of the knitted fabric, particularly in those instances where the yarn is formed of only two or three

threads to produce a very sheer fabric, the predominance of the lengthwise wales in the fabric renders it difficult to avoid the appearance in the fabric of circumferentially extending course-wise lines or bands of undesirable shadows or stripes, this being primarily due to the fact that in such fabrics the course-wise aspect thereof is generally of such uniformly smooth and even appearance and texture that any variations in the yarn from its specified physicals becomes immediately apparent in the knitted fabric, as, for example, in the form of a line when the variation from normal is limited to the length of a single course, or in the form of a shaded band or zone when the variation extends through the yarn or yarns comprising a plurality of successive courses.

From the foregoing, it will be understood that it is among the objects of the present invention to produce a knitted fabric for full-fashioned hosiery and the like which is characterized by the fact that the lengthwise wales or needle lines thereof are rendered far less conspicuous than in the conventionally knitted fabric, the fabric of the present invention being further characterized by the fact that in so subduing the effect of the said wales upon the eye, the aspect of the fabric considered course-wise is emphasized and rendered more pronounced.

More specifically, it is an object of the present invention to produce a full-fashioned knitted hosiery fabric in such manner that certain selected courses thereof, uniformly distributed through the length of the fabric, are rendered more pronounced and conspicuous than are the courses intervening said selected courses, thus imparting to the fabric a uniformly distributed course-wise ribbed effect which effectually eliminates in the fabric the appearance of objectionable shadows and the like which may be occasioned by the use of yarns having variations in the physicals thereof and at the same time enhances very considerably and provides an entirely new effect in the appearance of the fabric.

Another object of the invention is to provide a full-fashioned stocking knitted of a fabric wherein one or more courses thereof composed of a selected type of yarn are combined with one or more courses composed of a different type or types of yarn, thus producing a fabric in which different types of yarn are employed in different courses selected as desired to present a novel design in the fabric as well as to eliminate shadows and other such disfiguring conditions therein.

Other objects of the invention and advantages thereof, such as relate to the knitted fabric and

the method of producing the same, will be apparent more fully hereinafter.

In the accompanying drawing:—

Figure 1 is a side elevational view of a completed stocking constructed in accordance with and embodying the principles of the present invention;

Figure 2 is a diagrammatic representation upon an enlarged scale of a small portion of the knitted 10 leg fabric of the stocking; and

Figure 3 is a view similar to Figure 2 but showing a modification of the knitted fabric.

In order to obtain the aforementioned desired objects of the invention and to improve upon the 15 conventionally knitted fabrics, this invention contemplates the use of a plurality of independent lengths of yarn in the production of a single knitted fabric. In this respect it differs from the conventional method wherein a single continuous length yarn is employed to knit the sheer, non-reinforced portion of the stocking, such as the leg and the upper portion of the foot thereof. While it resembles generally the method of 20 knitting a fabric by the use of a plurality of independent yarns delivered selectively and in predetermined sequence by separately operable carriers to the knitting head of the machine, it differs from this latter known method in this 25 important respect, namely, that the independent 30 yarns which are separately delivered to two or more selectively actuated yarn carriers, instead of being substantially identical in their physical characteristics, are radically different with respect to at least two of the yarns so employed.

35 In other words, in practicing the present invention two or more independent yarns are delivered respectively through individual carriers to the knitting head of the machine at which point the carriers operate in the well-known conventional 40 manner to lay first one and then another length of each yarn along the bank of needles of the knitting head and so on in predeterminedly selected order to knit the several interlooped courses of the fabric whereby when the fabric 45 is completed there will be uniformly distributed throughout its extent courses formed of a yarn of entirely different physical characteristics from the yarn or yarns comprising the intervening courses. The yarns so employed in the knitting 50 of the fabric of the present invention may differ from one another not only in respect to the nature of the material of which they are formed but also in respect to the number of threads, the denier, the number of turns per inch, the 55 type of turn or twist imparted to the yarn, the direction of twist and in other such respects. For example, the yarns may be respectively of silk, cotton, wool or fiber, or any combination thereof, and if an all-silk fabric is to be produced, the several silk yarns employed may differ from one another in that they may be ingrain, boil-off, or gum silk.

From various observations and tests made of hosiery knitted of fabrics composed of different 60 combinations of yarns, it has been found that when a plurality of yarns which differ in their physical characteristics as above described are selectively employed to form uniformly distributed courses in the fabric a predominant feature and characteristic of all of the fabrics so produced is the appearance of pronounced course-wise ribs and the substantial disappearance 65 of the wales or needle lines. This results not only in the production of an entirely new 70 effect in hosiery fabrics but also eliminates the 75

appearance of any and all objectionable shadow bands and lines. It will be understood, of course, that by the term rib as employed hereinbefore is not meant a pronounced ridge or the like extending circumferentially about the stocking, that is, course-wise of the stocking fabric. As a matter of fact, the fabric produced in accordance with and embodying the principles of the present invention is of exceedingly uniform appearance and texture, the sheerness of the fabric being entirely dependent upon the denier and number of threads of the several yarns employed.

As a specific example of the method of knitting a fabric in accordance with the present invention, one may employ three different and independent yarns, designated *a*, *b* and *c* in Fig. 2, two of which yarns, that is, yarns *a* and *b* are each of three-thread, 13-15 denier, and 32 turns per inch while the third yarn *c* is of seven-thread, 13-15 denier, and 8 turns per inch. In this instance, all of the yarns are of silk, and when a fabric is knitted thereof in such manner that every third course is composed of the seven-thread yarn with the two intervening courses respectively composed of the three-thread yarns, a fabric is produced wherein the courses composed of the seven-thread yarn appear so predominantly in the fabric as to give it a pronounced horizontally striped appearance, the wales being so barely discernible as to make it difficult to judge from visual observation the gauge of the machine upon which the fabric was knitted.

Another example of a fabric knitted in accordance with the present invention is illustrated in Fig. 3 wherein three independent yarns *d*, *e* and *f* are employed each of which differs from one another in respect to the member of threads and number of turns in each. Thus, the first yarn *d* may be of two-thread, 13-15 denier, and 40 turns per inch, the second yarn *e* of three-thread, 13-15 denier and 32 turns per inch, and the third yarn *f* of four-thread, 13-15 denier, and 28 turns per inch. In producing a fabric of the three yarns last described, the several yarns may be employed in the order named to knit successive courses of the fabric, each course composed of a particular yarn being spaced from each other by two courses respectively composed of the other yarns. Due to the fact that in this latter example the yarns are not so markedly different in 50 respect to the number of threads in each as in the foregoing example, the course-wise lines are not so pronounced as in the foregoing example. Nevertheless, the fabric so produced distinctly shows horizontally extending lines of more or less 55 pronounced luster without perceptibly showing the wales, the results being thus similar in all material respects to those obtained by the use of the yarns as in the first example.

These results are obtained irrespective of the 60 number of different yarns employed so long as at least two or more such yarns are employed selectively and in predetermined sequence throughout the several interlooped courses of the fabric and in which at least one of the yarns differs materially in its physical characteristics from the other yarns, as in either the number of threads, the denier, the number of turns per inch, the material of which the yarn is basically formed, the direction of the twist and in other respects.

70 It is to be understood that in the foregoing specification and appended claims, the term "yarn" includes silk, either pure or artificial, or any other material adapted to be knitted into a hosiery fabric, or any combination thereof, and 75

which material may be in the form of a single strand or a plurality of strands, twisted or un-twisted, to form one or more threads of any desired denier and number of turns or twists per inch.

5 It will also be understood, of course, that the invention is susceptible of various changes from time to time, all without departing from the real spirit or general principles and it is accordingly 10 intended to claim the same broadly, as well as specifically, as indicated by the appended claims.

What is claimed as new and useful is:—

15 1. In a full-fashioned stocking, a sheer, non-reinforced knitted leg fabric therefor characterized in that two or more yarns of similar color but differing in the number of threads composing each yarn and accordingly in the commercial diameters thereof respectively compose different courses of the fabric, the said different yarns being selectively employed in predetermined course 20 sequence throughout the entire extent of said leg fabric to provide a uniform distribution of the

several yarns throughout the fabric whereby to produce in the latter a more pronounced appearance of the course-wise lines and a less pronounced appearance of the existing wale or needle lines.

2. In a stocking, a sheer, non-reinforced knitted 5 leg fabric wherein a plurality of separate yarns of similar color but differing in the number of threads composing each yarn and accordingly in the commercial diameters thereof are respectively employed in different courses of the fabric, the 10 said yarns being arranged in a predetermined selected sequence which is repeated throughout the length of the leg fabric, the courses formed of at least one of said yarns being of such pronounced appearance relatively to the remaining courses 15 as to import in the knitted fabric the appearance of course-wise lines as distinguished from the conventional wale or needle lines, the aspect of the latter in the knitted fabric being thereby materially subdued.

JACK KUGELMAN.
